UNITED STATES PATENT OFFICE

FRANK B. ALLEN, OF LOWER MERION TOWNSHIP, MONTGOMERY COUNTY, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

HEAT EXCHANGING TUBE

Application filed April 9, 1926. Serial No. 100,895.

This invention relates to the art of exchanging heat and is more particularly concerned with heat exchange tubes for furnaces.

5 It also relates to means for strengthening and/or longitudinally supporting and/or increasing the heat absorbing surfaces of heat exchange tubes while automatically maintaining the tube substantially free of, and of preventing the accumulation on the top of 10 the tubes of incombustible solids carried by the heated gases to which the tubes are exposed.

Various objects and advantages of my invention will appear in this specification which includes a description of certain structures and apparatus embodying my invention.

In the drawings accompanying and forming a part of this specification—

Fig. 1 is a vertical, longitudinal section through a furnace equipped with one form of apparatus embodying this invention parts being broken away;

25 Fig. 2 is an enlarged transverse sectional view of the apparatus of Fig. 1;

Fig. 3 is a fragmentary perspective showing the form of attachment of Figs. 1 and 2 to a much enlarged scale; and

30 Figs. 4, 5 and 6 are views similar to Fig. 3, but showing other forms of apparatus embodying my invention.

In furnaces, particularly those in which powdered coal is burned, the incombustible solids carried by the heated gases tend to collect on the heat exchanging tubes of the furnace with which the heated gases contact or which are otherwise exposed thereto whenever the top surface of the tubes is inclined at an angle less than the angle of repose of the solids, the solids tend to build up on the top of the tubes and gradually extend around the tubes so as to form hard thick clinkers which may substantially protect the tubes from direct contact with the heated gases and in extreme cases may entirely bridge the space between adjacent tubes. Among the practical results of the accumulation of such solids is a loss of heat transfer to the fluid within the tubes and a serious de-

crease in the area of the tubes exposed to the radiant heat of the gases. By my invention I am enabled to prevent the accumulation of such solids on the tops of heat exchange tubes in a furnace and to make the tubes substantially self-cleaning. By means of various forms of apparatus embodying my invention I am able also to provide desirable additional strength and support and especially in a direction longitudinally of the tubes.

60 In Fig. 1 I have shown fragmentarily a furnace of the powdered fuel burning type in which the flame is indicated at 1, the side walls of the furnace at 2, and the furnace bottom at 3 which is provided with an ash gate, not shown. A lorry car for carrying away ashes discharged from the furnace bottom may be brought into loading position below this door. Heat exchange tubes 4 adapted to contain water are shown supported in the opposite walls 2 and spanning the space therebetween where they are exposed to the heated gases and to incombustible solids carried by the gases. At either end of the tubes are shown headers 5 and 6 communicating with the tube 4 and also with tubes 7 and 8 which lead water to and from the headers 5 and 6, respectively. The tubes 7 and 8 preferably connect into the circulatory system of a water tube boiler 9.

65 It will be understood that incombustible solids such as ash, slag and the like carried by the heated gases and the flame 1 will tend to contact with the top of the tube 4 as they move downwardly under the influence of the flame and gas pressure and of gravity, and will lodge and remain on the tubes 4 if the top surfaces of the tubes are inclined at a lesser angle than the angle of repose of the solid materials. In the case of a round tube 70 the surface thereof is relatively flat at the top and such surface, even though relatively small, affords a lodging place for the solids. This is particularly true where the tubes are not longitudinally inclined at an angle 75 greater than the angle of repose of the solids, for example tubes 4, as shown herein.

80 Referring now more particularly to Fig. 3 in which I have shown one form of apparatus embodying my invention, a tube assembly 85

is shown in which 4 indicates the substantially round tube of the same number appearing in Figs. 1 and 2. This tube is provided with an attachment extending longitudinally for substantially the entire length of the tube and into the walls 2 where it may, in part at least, be supported, as by being received in recesses 2a. This attachment as shown consists of a plurality of saddle members 10, each having a substantially semi-circular surface 11 conforming to the outer surface of the tube 4 with which they contact, and yoke or covering members 12 securely held in close contact with the outer surfaces of the saddle members 10. Saddle members 10 are preferably extended above and below the tube 4 to permit the passage therethrough of bolts or rivets 13 which may be inserted and drawn up tightly against the members 12 while hot so as to result in close surface engagement between the members 10 and 12 and the members 10 with the tubes 4 when the attachment is at the temperature to which the tube is ordinarily exposed. The saddle members 10 are preferably provided above the top of tube 4 with one or more plates having surfaces 14 inclined to the horizontal at an angle greater than the angle of repose of the solids carried by the heated gases, and shown in these figures at an angle of approximately 60°. Solid material coming in contact with these surfaces will not lodge thereon but will pass down between the tubes onto the furnace bottom 3. By reason of the close surface contact of the members 12, 10 and 4, the effective heating surface of the tube 4 will be greatly increased and heat absorbed by the members 12 and 10 will be readily communicated to the tube 4. Moreover, the shape of the parts 10 and 12 and their assemblage as just described will result in a very rigid structure, being in effect a beam spanning the furnace, which, when supported at its ends by the walls 2 of the furnace, will not only be self-supporting, but will also strengthen and support the tube 4 longitudinally and also transversely and overcome the tendency of water tubes to buckle or sag as now frequently happens.

In the form of apparatus shown in Fig. 4, the saddle members 10a have been made quite short and are spaced apart as shown. The covering 12a is of one continuous piece extending around both sides and the top of the saddle members and clamped to these by any suitable means, such as the rivets or bolts above referred to. In this case, heat is received all along the covering 12a from the hot gases, and is conducted along the covering to the saddle members and by these to the tube. The slope of the upper sides of the covering is, of course, greater than the angle of repose of the ash and slag so that these drop off, as in the form first described.

In Fig. 5, I have shown another form of ap-

paratus embodying my invention, this modification taking the form of an angular sheet of metal 12b attached as by welding to a tube 4b. This attachment, or cover 12b, may extend for part or all of the length of the tube 70 4b and preferably, though not necessarily, extends into the walls 2 of the furnace or corresponding wall by which it may be supported in part. As shown this attachment 12b consists of sheet metal having two sloping sides 75 inclined at angles greater than the angle of repose of the solid material carried by the gases and is welded to the tube so as to cover the top thereof. Obviously, either one or two inclined surfaces per tube may be used and 80 the angle thereof varied without departing from the spirit of my invention so long as the angularity is sufficient to accomplish the desired purpose. The attachment 12b likewise strengthens the tubes longitudinally and increases the effective area thereof exposed to the heated gases as it is attached to the tube by a good heat conducting connection.

The form shown in Fig. 6 is very similar to that of Fig. 5, comprising an angular sheet metal strip 12c, welded or otherwise attached to a tube 4c. In this form, however, one side of the angular strip is vertical and the other inclined at a greater angle than the angle of repose of solid material, which may reach it, 95 and functions as do the two sloping sides of the preceding forms.

Having thus described my invention so that those skilled in the art may be enabled to practice the same, I have defined its scope by what is claimed, it being understood that variations, changes or modifications may be made in the structure which has been hereinabove described for purposes of illustration only, and that such changes and modifications are within the scope and spirit of my invention.

What is claimed is:

1. A heat exchange tube for a furnace said tube adapted to be positioned in the path of heated gases carrying incombustible solids, and an attachment therefor comprising a plurality of saddle members substantially surrounding the tube and extending lengthwise thereof and a yoke member having heat conducting connections with the saddle members, the said attachment having surfaces disposed above the top of the tube and inclined at an angle greater than the angle of repose of the said solids.

2. A tube assembly for substantially horizontal disposition in a furnace comprising a heat exchange tube, a deflector therefor, spacing means interposed between the deflector and tube at intervals, and means for securing the deflector and spacing means upon the tube with the upper surface of the deflector disposed at an angle greater than the angle of repose of solid material carried by gases of the furnace.

3. A tube assembly for substantially horizontal disposition in a furnace comprising a heat exchange tube, a deflector therefor, spacing means interposed between the deflector and tube at intervals, and means for securing close surface contact between the deflector, spacing means and tube whereby the heat absorbed by the deflector is readily communicated to the tube, the upper surface of the deflector being disposed at an angle greater than the angle of repose of solid material carried by gases of the furnace.

4. In combination with a powdered fuel burning furnace having a combustion chamber in which heated gases carrying combustible residues are forcibly directed downwardly, a plurality of heat exchange tubes extending across the lower portion of the chamber in the path of the downward flow of gases and spaced apart from each other, a metal extension projecting upwardly from each tube and having heat conducting connection therewith and provided with upper surfaces inclined at a greater angle than the angle of repose of ash and molten slag in the gases whereby the ash and molten slag will pass downwardly between the tubes without adhering thereto.

5. A wrought iron boiler tube of the character described having thereon a separately formed cover of good heat-transmitting properties extending longitudinally of the tube substantially from end to end thereof and being substantially apical in cross view, for the purposes specified.

6. A boiler tube of the character described having attached on the normally upper surface thereof a soot-deflecting structure extending longitudinally of the tube substantially from end to end thereof and being substantially triangular in cross view, for the purposes specified.

In testimony whereof I hereunto affix my signature this 24th day of March, 1926.

FRANK B. ALLEN.
